UNITED STATES PATENT OFFICE.

JOHN H. BALMER, OF MAPLEWOOD, NEW JERSEY.

DESIGN FOR A COMBINED BRACKET AND RACK.

Application filed June 4, 1925. Serial No. 13,655. Term of patent 14 years.

To all whom it may concern:

Be it known that I, JOHN HENRY BALMER, a citizen of the United States of America, and resident of Maplewood, in the county of Essex and State of New Jersey, have invented a new, original, and ornamental Design for a Combined Bracket and Rack, of which the following is a specification.

Reference is had to the accompanying drawing, in which—

Figure 1 is a perspective view of a combined bracket and rack showing my new design, as viewed from one side.

Figure 2 is a similar view of the opposite side.

I claim:

The ornamental design for a combined bracket and rack as shown.

JOHN H. BALMER.
